(57) CLAIM

The ornamental design for a band having spaced bullet cartridge elements, as shown and described.

DESCRIPTION

FIG. 1 is a perspective view of the band showing the left frontal view of my new design;

FIG. 2 is a front elevation view thereof showing the anterior side;

FIG. 3 is a rear elevation view thereof showing the posterior side;

FIG. 4 is a side elevation view thereof showing the right side;

FIG. 5 is a side elevation view thereof showing the left side;

FIG. 6 is a top plan view thereof; and,

FIG. 7 is a bottom plan view thereof.

The broken lines shown in the drawings illustrate portions of the band having spaced bullet cartridge elements and form no part of the claimed design.
